UNITED STATES PATENT OFFICE.

JAMES K. NORVELL, OF CHATTANOOGA, TENNESSEE.

SEAL FOR CARS AND THE LIKE.

1,012,417.

Specification of Letters Patent.

Patented Dec. 19, 1911.

Application filed August 23, 1911. Serial No. 645,568.

To all whom it may concern:

Be it known that I, JAMES K. NORVELL, a citizen of the United States, residing at Chattanooga, in the county of Hamilton and 5 State of Tennessee, have invented a new and useful Seal for Cars and the Like, of which the following is a specification.

This invention relates to seals for cars and other purposes, the object being to provide 10 a seal of this character which will be inexpensive to manufacture, efficient in use and which when applied to a car or other objects must be mutilated by breaking or rupturing to remove the same.

15 A further object of this invention is to provide a seal of this character which is folded from a single blank of material, which also reduces the expense in the manufacture thereof.

20 With the above and other objects in view this invention is embodied in the construction and arrangement of its parts as herein-after described and as pointed out in the appended claims, the invention being illustrated in the accompanying drawings, in 25 which similar reference characters indicate similar parts and in which—

Figure 1 is a plan view of the blank from which the seal is folded, parts broken away. 30 Figs. 2 and 3 are perspective views of two stages of the formation of the seal, parts broken away. Fig. 4 is a perspective of the completed seal. Fig. 5 is a longitudinal section thereof.

35 Referring specifically to the drawings, the blank from which the seal is folded, being preferably of suitable sheet metal, comprises a body constituting the sections 8 and 18 which are rectangular form and secured 40 together along one edge thereof. The body section 8 has an arm 10 projecting from one end thereof and a strap 9 projecting from the other end thereof, and from the outer edge of the said body section projects a flap 45

7. The outer edge of the said flap 7 is folded on the score 30 to form a lip 6, the outer or free end of the strap 9 is provided with an opening 28, and the outer end of the arm 10 is reduced in width to form a tongue 11 and

50 shoulders 29 at the inner end of the said tongue. The body section 18 is provided at one end with a short flap 26 having an opening 27 therein and at the other end with an elongated flap 17 having an opening 16 near 55 the outer or free end thereof.

In forming the seal, the outer end of the tongue 11 is bent back to form a catch 12, the same being bent back on the score 13 near the outer end thereof and the arm 10 is folded on the score 14 near the outer end thereof to bring the outer end and tongue 11 against same with the catch 12 disposed inwardly and the said arm is then bent on the score 21 over the body section 8. The flap 7 is then folded over the arm 10, the lip 6 passing over the edge of the said arm and the said parts are then folded over the body section 18, the flap 7 resting or coming against the said body section. The strap 9 is then passed through the opening 27 in 70 the flap 26 as shown in Fig. 3, and the said flap is then folded over the end of the body section 8. The flap 17 is then folded over the said parts coming against the body section 8, the strap 9 being passed through the 75 opening 16 and the end 15 of the said flap being folded over the end of the said parts as shown in Figs. 4 and 5 which completes the seal and renders same ready for application to the car or other objects. 80

It will be noted that the strap 9 in being passed through the flaps 26 and 17 prevents the relative parts from unfolding and securely locks them together.

The seal is applied to the hasp of the car 85 or to any other member in the usual manner and the free or other end thereof is inserted through the openings 27 and 16 to pass into the socket formed between the body sections and upon pulling the same outward, the 90 tongue 11 is caused to pass through the opening 28 in the end of the strap whereupon the catch 12 engages over the end of the strap to lock the end of the strap within the socket between the catch 12 and shoulders 29. Therefore after the strap has once been inserted through the socket thus formed by the various folded parts, it is impossible to remove same or remove the seal from the 95 car or other objects without mutilating the seal by breaking or buckling the same, and it will be seen that in this manner this seal becomes as effective as the customary seals in use. 103

If desired the strap 9 or the outer parts 105 of the socket portion of the seal may bear suitable numbers, or other printed matter, which will of course be governed by the uses to which the seal may be put. It is also understood that the invention is susceptible of 110

alteration in its details within the scope of the appended claims without departing from the spirit of the invention.

What is claimed is:

- 5 1. A seal of the character described formed from a blank and comprising body sections folded upon each other, a tongue within the body sections and having a catch on the end thereof, a strap projecting from one body section and having an opening in the outer end thereof, a flap folded from the other body section having an opening therein through which the strap passes, and a flap opposite the latter flap folded over the former body section and having an opening in the outer end thereof through which the said strap passes, whereby the outer end of the said strap is insertible through the said openings in the said flaps to be engaged by 20 the said tongue.
- 10 2. A seal of the character described formed from a blank and comprising body sections folded upon each other, an arm folded from one of the said sections and disposed within

the body sections, a tongue folded from the outer end of said arm against same, a catch folded from the outer end of the said tongue, a flap folded from the said body section over the said arm, a strap projecting from the said body section opposite the said arm and having an opening in the outer end thereof, a flap folded from the other body section having an opening therein through which the said strap passes, and a flap opposite the latter flap folded over the former body section and having an opening in the outer end thereof through which the said strap passes, whereby the outer end of the said strap can be inserted through the openings in the latter flaps to be engaged on the said tongue.

In testimony that I claim the foregoing as my own, I have hereto affixed my signature in the presence of two witnesses.

JAMES K. NORVELL.
